MACHINE WALKING DEVICE

Merwin Armstrong, Hinsdale, Ill.

Application July 24, 1947, Serial No. 763,229

10 Claims. (Cl. 180—8)

1

The present invention relates to a traction mechanism of the stepping or walking type for propelling heavy machines, such as excavators which require relatively large bearing areas for support and where for service it is desirable to have few moving parts in contact with the ground.

It is an object of the present invention to provide a traction mechanism that gives improved walking motion. This is accomplished while at the same time the construction is simplified and is well adapted for use on large and heavy machines.

The foregoing constitute some of the principal objects and advantages of the present invention, others of which will become apparent from the following description and the drawings, in which

Fig. 1 is a side elevational view of a machine, such as a drag-line excavator embodying the present invention, the shoes and legs being disposed in the raised or carrying position;

Fig. 2 is a fragmentary view corresponding to Fig. 1 but illustrating the shoes and legs advanced and lowered to the ground at the beginning of the step just before the body is lifted;

Fig. 3 is a view corresponding to Fig. 2 but illustrating the shoe in engagement with the ground and the machine body lifted ready for advancement during the next 90° rotation of the crank shaft;

Fig. 4 is a plan view of the machine illustrated in Fig. 1;

Fig. 5 is an end view of the machine;

Fig. 6 is an enlarged sectional view of a detail taken on line 6—6 of Fig. 1; and

Fig. 7 is a sectional view taken on line 7—7 of Fig. 6.

The present invention may be used in practice in various ways. For purposes of illustration one embodiment only is shown and this embodiment is illustrated as applied to a drag-line excavator. Obviously many modifications may be made in the embodiment shown without departing from the intended scope of the invention.

Referring now to the drawings the invention is illustrated as applied to a drag-line excavator generally indicated at 10 (in Fig. 1) that includes a body portion 12 that is mounted on a main base 13. A track member 14 is supported on the base 13 and a complementary track member 15 is supported on the underneath face of the body 12. Wheels or rollers 16 are disposed between the track members 14 and 15 so that the body 12 is adapted to rotate about the base 13 by virtue of the rollers 16 operating between the

2

tracks 14 and 15. As best shown in Fig. 4 the body 12 includes a pair of outwardly projecting housing portions 17 that are on opposite sides of the body 12.

Extending entirely across the body 12 and journaled in the housing portion 17 is a horizontally disposed shaft 18, the bearings for the shaft being illustrated at 19. Disposed parallel to the shaft 18 and mounted in the machine body 12 is a second shaft 20 journaled at its opposite ends as indicated at 21. Mounted adjacent to one end of this shaft 20 is a drive gear 22. A motor or engine 23 is housed in the machine body 12 and is provided with a pinion 24 that meshes with the drive gear 22. A pinion 25 is mounted on the opposite end of the shaft 20 and is adapted to mesh with a gear 26 that is mounted on the shaft 18. Thus the motor 23 is adapted to drive the shaft 18 through the pinion and gear 24, 22, shaft 20 and pinion-gear set 25 and 26.

Disposed on the opposite sides of the machine body 12 are feet or shoes 27 (see Figs. 1, 4 and 5). Each foot 27 is provided with upstanding ear portions 28 (see Fig. 1) to which are pivotally connected the lower end of a leg 29 by pin 30. Mounted on each end of the shaft 18 is an eccentric or crank 31 that is provided with a crank arm 32, the end of which arm is journaled in the upper or free end of the leg as at 33.

Referring now to Fig. 4 a shaft 34 is journaled on its opposite ends as at 35 in each of the housing portions 17 of the machine body 12 and each of these shafts extends parallel to the main shaft 18. For purposes of this description the direction of movement of the machine body 12 is from right to left as indicated by the arrow A in Fig. 1 so that with respect to the direction of movement of the machine the left hand edge of the body 12 will be referred to as the forward edge and is identified by the reference character 36. Thus the shaft 34 is rearwardly spaced with respect to the shaft 18. Mounted on the outer end of each of the shafts 34 is a crank 37 having a crank arm 38. Journaled to the free end of the crank arm 38 is a connecting rod or link 39 that is pivotally connected to an ear 41 (see Fig. 4) on the leg 29 intermediate the upper and lower ends of the leg.

Again referring to Fig. 4 a suitable drive such as a sprocket chain drive generally indicated at 42 is provided between the shafts 18 and 34 so that each of the shafts 34 receives its rotated power from the shaft 18 and is driven at the same speed as the shaft 18.

There is thus described a traction mechanism

that is simple and yet effective for moving large and heavy machinery. As shown in Fig. 1 the shaft 18 normally operates in a counterclockwise direction and as shown the crank 31 is rotated to the first 90° from a substantially horizontal position to a vertical upright position where each foot 27 is raised off the ground to its uppermost position, each foot advancing somewhat in a horizontal direction during this first 90°. During the next 90° rotation of the crank 31 the shoes or feet 27 are advanced and placed on the ground as indicated in Fig. 2. The cranks are then rotated to an additional 90°, during which time one edge of the base 13 is raised off the ground as indicated in Fig. 3 and then during the next 90° operation of the cranks the machine is moved forward dragging the right hand end (Fig. 3) of the base along the ground. As the crank rotates from the position shown in solid lines in Fig. 3 the forward edge of the machine base 13 is lowered until it finally engages the ground where the entire machine has advanced a predetermined distance depending upon the relationship between the various arms and cranks. The operation can then be repeated so as to continue the advancement of the machine.

During this operation of the main crank 31 the auxiliary shaft 34 is caused to operate at the same speed as the main shaft 18 so as to turn the cranks 37. These cranks 37 through their respective links 39 serve to guide the legs 29 and to impart to the legs a substantially horizontal position. Thus the cranks 31 provide vertical lift to the shoes or feet 27 and the cranks 37 impart horizontal motion.

Mounted on top of each of the housing portions 17 of the machine body 12 is an equalizer generally indicated at 43 that includes a pair of spaced cables 44 fixed at their lower ends as at 40 to one of the feet or shoes 27 at positions equidistant from the ends of the shoes. Each of these cables 44 passes over a pulley 45 (Fig. 5) that is disposed substantially vertically above the shoe 27 and then passes over a second pulley 46. A weight 47 is fixed to the free end of each cable 44. This weight is adapted to slide up and down on an inclined surface 48 that is formed on a frame member 49. One end of this frame member 49 is pivotally secured to a bracket 50 that is mounted on top of the housing 17. As best shown in Figs. 1 and 5 the forward end of each of the frame members 49 is provided with an I-beam 65 that rests on top of a roller 66 that is journaled in angle members 67. These angle members 67 are mounted on top of each of the legs 29 so that the forward end of each of the frame members 49 is actually supported on the adjacent leg 29. The weights 47 on the cables 44 are of equal weight so that as the foot or shoe 27 is raised above the ground these weights 47 through their respective cables 44 are free to slide on the surface 48 and if the shoe tilts due to an accumulation of mud or the like, the weight on the corresponding side comes to rest on a stop 70 so that the other weight can act to return the foot or shoe 27 to the horizontal position.

Each of the legs 29 is provided at its lower end with a bearing member 51, shown in Figs. 6 and 7, that comprises a pair of plates 52 and 53 fastened together as at 54. This bearing member 51 has a spherical socket 55 in which is rotatably mounted a rotatable member 56 having spherical surfaces adapted to cooperate with the faces 55.

The rotatable member 56 is apertured to receive the pin 30. This pin 30 is held in the ears 28 on

the leg 27. The lower face of the bearing member 51 is seated on a bearing block 57, there being provided cooperating arcuate engaging faces. The bearing block 57 is slidably supported on a plate 58 that in turn rests on a pair of I-beams 59. The plate 58 is channeled at 60 to hold the bearing block 57 in sliding relationship. The block 57 is apertured at 61 to receive rod 62 that projects beyond each ear 28. Compression springs 63 are mounted on the ends of each rod 62 and a spring seat 64 is threaded onto each end of the rod 62. Each spring 63 is held between one of the seats 64 and the adjacent ear 28. These springs 63 normally center the bearing block 57 between the ears 28 but permit sliding movement of the block to take place along the rods 62.

Throughout this description the members 31 and 37 have been referred to as cranks. It is recognized, of course, that conventional eccentrics, other than true cranks may be employed, it being important only that eccentricity be provided to furnish a lever or crank arm.

With the arrangement thus described, the legs 29 are disposed in a substantially vertical position throughout the lifting portion of the cycle of crank 31 but is moved to a sloping or leaning position in the direction of movement of the machine body 10 during the last portion of the cycle of the crank 31 while the machine body 10 is being lowered. This leaning condition of the legs 29 is brought about by virtue of the fact that the crank arm for crank 37 is longer than the crank arm for crank 31. Thus the legs serve as direct columns during lifting of the machine body but serve to ease the weight to the ground rather than to allow the weight to drop freely from the mechanism height.

I claim:

1. The combination of a frame, substantially vertically disposed legs at each side of the frame, a foot pivotally secured to the lower end of each leg, crank means including a crank arm disposed adjacent to the upper end of each leg, means on the frame mounting each crank for rotation about a horizontal axis, each leg being mounted adjacent to its upper end on a crank arm and of sufficient length to bear the feet on the ground, second crank means including a crank arm spaced longitudinally of the frame with respect to each of the first mentioned cranks, means mounting each of the second cranks for rotation about a horizontal axis, power means mounted on the frame connected in driving relationship with the cranks, and a link connecting the crank arm of each of the second cranks and the adjacent leg intermediate the upper and lower ends of the leg.

2. The combination of a frame, substantially vertically disposed legs at each side of the frame, a foot pivotally secured to the lower end of each leg, crank means including a crank arm disposed adjacent to the upper end of each leg, means on the frame mounting each crank for rotation about a horizontal axis, each leg being mounted adjacent to its upper end on a crank arm and of sufficient length to bear the feet on the ground, second crank means including a crank arm spaced longitudinally of the frame with respect to each of the first mentioned cranks and disposed substantially parallel therewith, means mounting each of the second cranks for rotation about a horizontal axis, power means mounted on the frame connected in driving relationship with the cranks, and a link connecting the crank arm of each of the second cranks and the adja-

cent leg intermediate the upper and lower ends of the leg.

3. The combination of a frame adapted to move in one direction and having a leading edge with respect to the direction of travel, substantially vertically disposed legs at each side of the frame spaced rearwardly from the leading edge, a foot pivotally secured to the lower end of each leg, crank means spaced rearwardly from the leading edge including a crank arm disposed adjacent to the upper end of each leg, means on the frame mounting each crank for rotation about a horizontal axis, each leg being mounted adjacent to its upper end on a crank arm, second crank means including a crank arm spaced further away from the leading edge than the first crank means, means mounting each of the second cranks for rotation about a horizontal axis, power means mounted on the frame connected in driving relationship with the cranks, and a link connecting the crank arm of each of the second cranks and the adjacent leg intermediate the upper and lower ends of the leg.

4. The combination of a frame, substantially vertically disposed legs at each side of the frame, a foot pivotally secured to the lower end of each leg, crank means including a crank arm disposed adjacent to the upper end of each leg, means on the frame mounting each crank for rotation about a horizontal axis, each leg being mounted adjacent to its upper end on a crank arm and of sufficient length to bear the feet on the ground, second crank means including a crank arm spaced longitudinally of the frame with respect to each of the first mentioned cranks, means mounting each of the second cranks for rotation about a horizontal axis, power means mounted on the frame connected in driving relationship with the cranks, and a link connecting the crank arm of each of the second cranks and the adjacent leg intermediate the upper and lower ends of the leg, and means on the frame and operatively connected to each foot for maintaining the foot horizontal.

5. The combination of a frame, substantially vertically disposed legs at each side of the frame, a foot pivotally disposed to the lower end of each leg, crank means including a crank arm disposed adjacent to the upper end of each leg, means on the frame mounting each crank for rotation about a horizontal axis, each leg being mounted adjacent to its upper end on a crank, second crank means including a crank arm spaced longitudinally of the frame with respect to each of the first mentioned cranks, means mounting each of the second cranks for rotation about a horizontal axis, power means mounted on the frame connected in driving relationship with the cranks, a link connecting the crank arm of each of the second cranks and the adjacent leg intermediate the upper and lower ends of the leg, means providing linear movement of the foot on the leg, and means on the frame and operatively connected to each foot for maintaining the foot horizontal.

6. The combination of a frame, substantially vertically disposed legs at each side of the frame, a foot pivotally disposed to the lower end of each leg, crank means including a crank arm disposed adjacent to the upper end of each leg, means on the frame mounting each crank for rotation about a horizontal axis, each leg being mounted adjacent to its upper end on a crank, second crank means including a crank arm spaced longitudinally of the frame with respect to each of

the first mentioned cranks, means mounting each of the second cranks for rotation about a horizontal axis, power means mounted on the frame connected in driving relationship with the cranks, a link connecting the crank arm of each of the second cranks and the adjacent leg intermediate the upper and lower ends of the leg, means providing linear movement of the foot on the leg, and means on the frame and operatively connected to each foot for maintaining the foot horizontal, said last named means including an equalizer arm, means pivoting one end of said equalizer arm on the frame, and means mounting the other end of the equalizer arm for sliding movement on the top of the leg.

7. The combination of a frame, substantially vertically disposed legs at each side of the frame, a foot pivotally secured to the lower end of each leg, crank means including a crank arm disposed adjacent to the upper end of each leg, means on the frame mounting each crank for rotation about a horizontal axis, each leg being mounted adjacent to its upper end on a crank arm aforesaid and of sufficient length to bear the feet on the ground, second crank means including a crank arm spaced longitudinally of the frame with respect to each of the first mentioned cranks, means mounting each of the second cranks for rotation about a horizontal axis, power means mounted on the frame connected in driving relationship with the cranks, and a link connecting the crank arm of each of the second cranks and the adjacent leg intermediate the upper and lower ends of the leg, and means on the frame and operatively connected to each foot comprising for maintaining the foot horizontal comprising an arm pivotally mounted on the frame and adapted to move up and down with each foot and weighing means operatively connected to the foot and actuated by the pivoted arm to maintain the foot in the horizontal position.

8. The combination of a body mounted on a ground bearing base and adapted to rotate about a vertical axis with respect to the base, a pair of parallel eccentric driving elements mounted on each side of the body and spaced longitudinally of each other with respect to the body, a leg on each side of the body trunnioned at its upper end to one of the eccentric elements and at its lower end to an auxiliary ground bearing foot, a link connecting said leg to the other eccentric element of said pair, and power means on the body rotating each eccentric element about a horizontal axis.

9. The combination of a body mounted on a ground bearing base and adapted to rotate about a vertical axis with respect to the base, a pair of parallel eccentric driving elements mounted on each side of the body and spaced longitudinally of each other with respect to the body, a leg on each side of the body trunnioned at its upper end to one of the eccentric elements and at its lower end to an auxiliary ground bearing foot, a link connecting each of the second eccentric elements and the adjacent leg intermediate the upper and lower ends of the leg, and power means on the body for rotating the eccentric elements in the same direction and at the same rotative speed.

10. The combination of a body mounted on a ground bearing base and adapted to rotate about a vertical axis with respect to the base, a pair of parallel eccentric driving elements mounted on each side of the body and spaced longitudinally of each other with respect to the body, a leg on each side of the body trunnioned at its

upper end to one of the eccentric elements and at its lower end to an auxiliary ground-bearing foot, a link connecting said leg to the other eccentric element of said pair, and power means on the body rotating each eccentric element about a horizontal axis, and means on the frame operatively connected to each foot for maintaining the foot horizontal.
